UNITED STATES PATENT OFFICE.

SAMUEL B. STINE, OF OSCEOLA MILLS, PENNSYLVANIA, ASSIGNOR OF TWO-THIRDS TO GEORGE M. BRISBIN AND D. R. GOOD, BOTH OF SAME PLACE.

MINING-MACHINE.

SPECIFICATION forming part of Letters Patent No. 443,586, dated December 30, 1890.

Application filed October 26, 1889. Serial No. 328,255. (No model.)

To all whom it may concern:

Be it known that I, SAMUEL B. STINE, a resident of Osceola Mills, in the county of Clearfield and State of Pennsylvania, have invented a new and useful Improvement in Mining-Machines; and I do hereby declare the following to be a full, clear, and exact description thereof.

My invention relates to mining-machines—
10 that is, machines for undercutting coal in mines—and has special reference to machines of this kind operated by electric or like power obtained from a motor on a separate movable car, apparatus for this purpose being shown
15 in Letters Patent No. 411,200, granted to F. M. Lechner on September 17, 1889.

The object of my invention is to improve the construction of this class of machinery where the cutting apparatus is at the forward 20 end of the carriage and is operated from a cross-shaft at the rear end of the carriage by driving-chains.

The apparatus forming the subject-matter of the present application comprises certain 25 improvements in the driving and feeding mechanism, which will be hereinafter particularly described and claimed.

To enable others skilled in the art to make and use my invention, I will describe the same 30 more fully, referring to the accompanying drawings, in which—

Figure 1 is a plan view of the machine embodying my invention. Fig. 2 is a longitudinal section on the line 2 2, Fig. 1. Fig. 3 is a 35 rear view of the machine, and Fig. 4 is a side view of the rear part of the machine.

Like letters of reference indicate like parts in each of the figures.

My invention is illustrated in connection 40 with a machine having a cutter-bar driven at the forward end by cog-gear, such as illustrated in Letters Patent No. 356,699, granted to me January 25, 1887, this being an improved form of machine, which has been 45 found efficient for the purpose.

The machine has a bed *a*, on which is mounted a sliding frame or carriage *b*, the bed as generally constructed having the two side bars, or, as they are generally termed, 50 "housings" *c*. At the forward end of the stationary bed is the cross bar or brace *d* and

at the rear end thereof the cross-bar or brace *d*, which bars, with the side bars or housings *c*, form the body of the stationary bed. Mounted in the stand or bracket *e*, at the rear 55 of the bed *a* and at one side thereof, is the vertical shaft *e*, which carries at its upper end the grooved pulley *f*, around which the driving-rope from the electric motor on the separate movable car or carriage passes, so as 60 to rotate this vertical shaft *e*. The shaft *e* has the bevel-pinion *e*², which meshes with the bevel-pinion *g*¹ on the end of the grooved shaft *g*, this grooved shaft being mounted in the stand-bearing *e*¹ and in a box or bearing 65 *g*² at the forward end of the bed, and the shaft extending longitudinally of the bed and, as preferred by me, along one side of the bed above one of the housings. The sliding frame or carriage *b* has the side bars *b*¹ running in 70 the housings *c*, and at the rear end of the carriage has the plate *h*, on which the power mechanism is mounted. It has at the forward end thereof the cutter-bar or other cutting mechanism *i*, and in the construction 75 shown has back of the same the forward chain-shaft *i*¹, which connects with the cutter-bar by the cog-gearing *i*² *i*³.

At the rear of the machine, and on the same horizontal plane as the grooved shaft *g*, is the 80 cross-shaft *k*, which is mounted in bearings *k*¹ and carries at the end, near the grooved shaft *g*, the bevel-gear *k*². The bevel-gear *k*² meshes with the bevel-gear *l*, which fits around the grooved shaft *g* and engages therewith by a feather, said bevel-gear being journaled in a bearing *l*¹ extending up from the plate *h*, and the bevel-gear *l* moving with the carriage *b*¹ and acting to transmit the power from the grooved shaft *g* to the cross-shaft *k*. 90 Mounted on said plate, but back of and below the cross-shaft *k*, is the chain-driving shaft *m*, which is driven from the shaft *k* by the small pinion *k*³ meshing with the large pinion *m*¹ on said shaft *m*. The said shaft *m* 95 carries a series of sprockets, over which pass the driving-chains *n*, which extend to the forward end of the carriage and pass around sprockets on the forward chain-shaft *i*¹, so transmitting power to said shaft and enabling 100 it through the pinions *i*² *i*³ to drive the cutter-bar.

In order to feed the machine forward and draw it back after the making of the cut, I employ a rotating screw-bar p , which extends longitudinally of the machine and moves with the traveling carriage, the screw-bar engaging with a nut d^2 on the forward cross-brace d' of the stationary bed and being mounted at its rear end in a suitable bearing p' on the plate h . In order to rotate this screw-shaft 5 to feed the carriage forward, I employ the feeding worm-gear r , and to rotate it to draw the carriage back I employ the worm-gear s , which worm-gears are mounted loosely on the rear end of the screw-bar p , and are thrown 10 into engagement therewith by the clutch t , operated by the clutch-lever t' . The worm-gear r , for feeding the carriage forward, is engaged by a worm r' on the chain-driving shaft m , and the worm-gear s , for withdrawing or 15 receding the carriage, is engaged by the worm-gear s' on the cross-shaft k , said worm being of large diameter, so that it meshes with the worm-gear s , even though the cross-shaft k extends on a higher horizontal plane than the 20 cross-shaft m . The pitch of these worms and worm-gears is such as to provide a comparatively slow feeding action from the slower-running shaft m and a comparatively rapid receding action from the shaft k , which generally rotates at about four times the speed 25 of the shaft m .

In the operation of the machine constructed as above described the bed of the machine is placed opposite the body of coal to be cut and 30 the driving-rope from the electric motor or other power apparatus on the movable car is placed around the pulley f and the motor adjusted so as to bring the proper tension on the rope. The power is transmitted from this 35 rope, through the pulley f , to the vertical shaft e , and thence to the grooved shaft g , and by the bevel-gearing l k^2 to the cross-shaft k , from said shaft by gearing k^3 m' to the chain-driving shaft m , and thence by the chains to 40 the cutter-bar, as above described, the cutter-bar being rotated at a high speed, and, in the apparatus shown, cutting in an upward direction, which is found very desirable in such machines. The operator then, by means of 45 the clutch-lever t' , throws the clutch into engagement with the worm-gear r , and through the worm r' on the shaft m the screw-bar p is rotated, so as to feed forward the carriage and feed the cutter-bar into the body of the 50 coal. As soon as the cut is made the operator draws the clutch out of engagement with 55

the worm-gear r and throws it into engagement with the worm-gear s , in which case the worm s' on the cross-shaft k operates to rotate the screw-bar in the opposite direction, 60 and so to draw back the carriage from the body of coal, the carriage being drawn back rapidly, and in this way the cut is completed. As soon as the carriage is drawn back the machine is moved the proper distance to make 65 another cut, the driving-rope adjusted to the proper tension, and the operation repeated.

The machine constructed as above described is strong, as the parts thereof are few and simple and may be made heavy, so that 70 they will not get out of order. By placing the longitudinally-extending grooved shaft g at the side of the machine I am enabled to drive the cross-shaft therefrom by the ordinary cog-gearing and provide for the proper 75 rotation of the different parts necessary for transmitting power and operating the machine.

Practical use of a machine constructed as above described has proven it to be efficient 80 for the purpose.

No claim is made in this application for the specific improvements shown herein, which are set forth and claimed in the application filed by me September 20, 1889, Serial No. 85 324,589.

What I claim as my invention, and desire to secure by Letters Patent, is—

In a mining-machine, the combination of a bed having therein a grooved power-shaft and 90 a nut at the forward end thereof, a carriage traveling thereon and having a cutting apparatus at the forward end, a cross-shaft near the rear of the carriage, and power-connections between the grooved power-shaft and 95 said cross-shaft, a cross-shaft below said cross-shaft and gearing therewith and connected by chains with the cutting apparatus, a screw-bar extending longitudinally below said cross-shafts and engaging with said nut on the bed, 100 a large worm on the upper cross-shaft, a small worm on the lower cross-shaft, and worm-gears mounted on said screw-bar with which said worms engage, substantially as and for the purposes set forth.

In testimony whereof I, the said SAMUEL B. STINE, have hereunto set my hand.

SAMUEL B. STINE.
